(57) **CLAIM**

The ornamental design for an LED infrared skin-treatment device with charging base as shown and described.

DESCRIPTION

FIG. 1 is a front elevational view of an LED infrared skin-treatment device with charging base, shown without the charging base shown;

FIG. 2 is a right side elevational view thereof;

FIG. 3 is a rear elevational view thereof;

FIG. 4 is a left side elevational view thereof;

FIG. 5 is a top plan view thereof;

FIG. 6 is a bottom plan view thereof;

FIG. 7 is a front perspective view thereof;

FIG. 8 is a front elevational view of an LED infrared skin-treatment device with charging base, shown with the charging base shown;

FIG. 9 is a right side elevational view thereof;

FIG. 10 is a rear elevational view thereof;

FIG. 11 is a left side elevational view thereof;

FIG. 12 is a top plan view thereof;

FIG. 13 is a bottom plan view thereof; and,

FIG. 14 is a front perspective view thereof.

The broken lines for the LEDs at the front face of the head, the vent holes on the back, and the battery cover depict environment only and form no part of the claimed design. The broken line circles on the bottom of the LED infrared skin-treatment device and the broken lines on the charging base in FIG. 10 depict portions of the LED infrared skin-treatment device with charging base that form no part of the claimed design.
